BAIT BUCKET

Robert M. Brankstone, Memphis, Tenn.

Application June 2, 1949, Serial No. 3,013

Term of patent 14 years

(Cl. D31—4)

To all whom it may concern:

Be it known that I, Robert M. Brankstone, a citizen of the United States of America, residing at Memphis, in the county of Shelby and State of Tennessee, have invented a new, original, and ornamental Design for a Bait Bucket, of which the following is a specification, reference being had to the accompanying drawings, forming a part thereof.

In the drawings:

Fig. 1 is a perspective view of a bait bucket, showing my new design.

Fig. 2 is a side elevation of the bait bucket; and

Fig. 3 is a plan view thereof.

I claim:

The ornamental design for a bait bucket, substantially as shown.

ROBERT M. BRANKSTONE.
